UNITED STATES PATENT OFFICE.

THEODORE W. FOSTER, OF PROVIDENCE, RHODE ISLAND, ASSIGNOR TO THEODORE W. FOSTER & BRO. CO., OF PROVIDENCE, RHODE ISLAND, A CORPORATION OF MAINE.

DESIGN FOR A MIRROR, BRUSH, OR SIMILAR ARTICLE.

Application filed May 4, 1922. Serial No. 2,089. Term of patent 3½ years.

To all whom it may concern:

Be it known that I, THEODORE W. FOSTER, a citizen of the United States, residing at the city of Providence, county of Providence, and State of Rhode Island, have invented a new, original, and ornamental Design for Mirrors, Brushes, or Similar Articles, reference being had to the accompanying drawing, forming a part thereof.

The figure is a view showing the back and handle of a mirror, brush, or similar article, illustrating my new design.

I claim:

The ornamental design for a mirror, brush, or similar article, as shown.

THEODORE W. FOSTER.
